GRAIN SEPARATOR

Toshihiko Satake, Hiroshima-ken, Japan

Application June 15, 1953, Serial No. 361,718

Claims priority, application Japan January 11, 1953

4 Claims. (Cl. 209—479)

This invention relates to separation of grain or, more particularly, to a machine for separating grain from a grain mixture containing impurities and to a method of separating the same. In treating grain such as rice, wheat, barley, oats or beans to a marketable state after it is harvested and stored, it is common to have the grain in a refined state by separating and removing sand particles, fine stones, unhulled rice, bran, etc. contained in the grain mixture. However, there have been no machine and method for such separation and removal. Filtration by screens has been rather common for such purpose. However, said filtration by screens is only by the size of the grain particles and therefore cannot separate such impurities as fine stones which are higher in specific gravity but which may be of the same size as the particles of the basic grain. Thus, unhulled rice or bran will not be separated if it is of the same particle size as the basic grain.

This invention can surely remove impurities which may be of the same size as the grain but are different in specific gravity or, in other words, which may not be different in size from the grain but are different only in specific gravity.

An object of this invention is to provide an apparatus convenient to remove impurities from grain such as rice, wheat, barley, oats or beans.

Further objects of this invention are to provide a method of and an apparatus for continuously performing the above treatment.

This invention shall now be explained with reference to the drawings which only show embodiments of this invention and to which, needless to say, this invention is not to be limited.

Figure 1 of the drawing is a sectioned side view of a separator of this invention. Figure 2 shows a multiple type apparatus of this invention.

In the separator shown in Figure 1, vertical wall 10 bears rotary disc 12 rotatably on its flat bottom part 11, rotary disc 12 has conical projection 14 at its center and outer peripheral end surface 13 of said disc is positioned against the inner peripheral end surface of range-flange 15. Vertical wall 10 is slightly expanded upwardly and its upper end part is somewhat bent inwardly. Discharge tube 16 having its lower end at such a distance from the upper surface of said disc as will allow grain which is to be treated to flow out sufficiently on said disc is suspended above disc 12. Said tube 16 is coaxial with rotary disc 12 and ring shaped vertical wall 10. The lower part of said tube is flared in conformity with outside surface 17 of conical part 14 of disc 12.

Therefore, the grain to be treated fed into tube 16 flows continuously down onto disc 12 out of the above flared part. In this case, disc 12 is fixed to a shaft rotated by a proper driving machine and therefore rotates. The grain mixture fed into filtration chamber 18 formed by vertical wall 10 and disc 12 therefore has the shape of flow adjusted by the resistance between the inside surface of vertical wall 10 and the mixture. Thus the part of

2

the grain mixture which is high in specific gravity and has a lower frictional coefficient will have a smaller resistance to flow and will be subjected to a greater centrifugal force. Therefore, it will cause a relative motion with the other part of the grain mixture, will move toward vertical wall 10 and will have a tendency to rise along said wall when it strikes against the wall, a flow shown by arrow A is caused.

In case the grain forming said flow is, for example, rice, uncleared rice will cause flow A, unhulled rice lighter than that will assemble in the upper layer part of flow A and, at a part nearer to the center, revolutionary flow B will be produced. Therefore, if suction pipes 19 and 20 opening toward those two flows suck up said flows respectively, the parts of the grain forming those flows will be easily removed.

Heavy uncleared rice can be automatically taken out of chamber 18 through exhausting passage 21 provided near the upper part of wall 10 rather than by suction.

The embodiment shown in Figure 2 is of a multiple type wherein several units are lapped vertically over one another, the apparatus shown in Figure 1 being one unit.

In this apparatus, a grain mixture containing impurities is simultaneously fed to each chamber from a hopper disposed above overlapped chambers. In each chamber, the fed mixture is subjected to filtration. The filtrate grain and filtration residue from each chamber are separately collected through respective guide passages.

The apparatus shown in Figure 2 has cylindrical base portion 22 and has horizontal shaft 23 driven by a proper driving source on the wall. Bevel gear 24 is fixed to horizontal shaft 23 and is engaged with bevel gear 28 fixed to vertical shaft 27 borne between horizontal walls or support members 25 and 26 formed with a spacing left between them in base portion 22.

Lower friction disc 30 which has a shallow annular groove 29 arc-shaped in the radial direction is fixed to the part of shaft 27 projecting above horizontal wall 26 and is rotated through gears 24 and 28 by the rotation of driving shaft 23.

A support member formed in the upper part within base portion 22 bears the lower portion of the central rotating shaft 31 of this apparatus. Lower portion 32 of said shaft 31 extends below bearing means 33. Upper friction disc 34 which is similar to said lower friction disc 30 is fixed to said lower portion 32. Upper and lower friction discs 34 and 30 have their respective annular grooves 35 and 29 facing each other. Two rotating rolls 36 and 37 are disposed between these grooves and the outside peripheries of said rollers are in frictional contact with the grooves of said friction discs.

Rotating rolls 36 and 37 are pivoted by respective yokes 38 and 39. The shank portions of said yokes extend outwardly through the wall of base 22. Those extended parts have respective gears or worm wheels 40 and 41.

When gears or wheels 40 and 41 are rotated simultaneously in opposite directions at the same rate by means not shown, friction rolls 36 and 37 vary their inclination 60 an equal amount but in opposite directions. Therefore, the contact position of the respective rolls in grooves 29 and 35 vary and thus, with a constant rotation of disc 30, the rotation of disc 34 can be varied in accordance with the inclination of rolls 36 and 37. As a result, the rotation per unit time of shaft 31 can be varied continuously without interruption.

The upper edge of base 22 has portion 42 expanding radially in the shape of a circular flange. Said portion 42 forms the bottom part of the third chamber C. Outside wall 43 of said third chamber is attached to the outside periphery of bottom plate 42. Cylindrical bearing member 44 is fixed to the inner periphery of bottom plate 42

and has upper bearing 45 for central shaft 31 at the upper end of said member.

A conical central portion forming inside wall 46 of the third chamber C is fixed to shaft 31 just above bearing 45. Rotary disc 47 having an area sufficient to cover the whole surface of said bottom plate 42 is formed horizontally. A slight clearance exists between the back surface of disc 47 and bottom plate 42 and disc 47 can rotate above plate 42. Cylindrical inside wall 48 forming chamber C of a cross-section like that of a hopper opposite outside wall 43 projects from the upper surface of rotating disc 47. The upper end of inside wall 48 is slightly above the level of the upper end of outside wall 43. Several separators 49 are provided to project outside said inside wall 48. Cylindrical member 50 which is intended to be a guide plate for the feed of grain is fixed at the outer ends of said separator. A ring shaped passage is formed between said members 48 and 50 and serves to guide the grain to be fed into the chamber C. The outside periphery of ring shaped horizontal plate 51 is fixed to the upper edge of outside wall 43 of the chamber C. The lower end of outside wall 52 of second chamber B is supported along the inner periphery of said ring plate 51. As a result, said outside wall 52 is stationarily mounted on base 22 through outside wall 43 of the chamber C.

The bottom plate of second chamber B is omitted and, instead, rotary circular disc 53 becomes a bottom plate. Said rotary disc 53 is fixed to the shaft 31 at the center. Ring shaped guide 56 formed by two conical walls 54 and 55 thrusts through said bottom plate. The lower end of said ring shaped guide 56 opens at the upper end of said ring shaped passage and the upper end thereof projects slightly above the level of outside wall 52 and opens there. Therefore, grain from above is led directly into chamber C without being led through chamber B. Cylindrical plate 58 is secured outside above guide 55 by several separators 57 through a ring shaped clearance between it and wall 55. Passage 59 formed by said plate 58 and wall 55 serves to feed grain from above to chamber B.

The upper edge of outside wall 52 of chamber B supports the outer periphery of ring plate 60 as in the case of chamber C. Said ring plate 60 supports at its inner periphery the lower end portion of inverter-conical ring shaped outside wall 61 of chamber A. Chamber A, like chamber B, has no bottom plate, rotary disc 62 serving as a bottom plate. Said rotary disc 62 is fixed to shaft 31 at its center so as to rotate with the rotation of said shaft 31. This is the same as in discs 53 and 47. Two circular passages 63 and 64 having common separating wall or internal wall 66 thrust through rotary disc 62 at the central part. Passages 63 and 64 are formed of three outwardly inclined circular walls formed in one body together with disc 62, namely, outside wall 65, internal wall 66 and inside wall 67. Ring-shaped vertical plate 69 is fixed to the outside surface of outside wall 65 through several separators 68. Said plate 69 forms feeding guide 70 between it and outside wall 65 in cooperation with said wall 65.

Outside wall 61 of first chamber A supports cover plate 71 at its upper edge portion. Said cover plate 71 has opening 72 at its center and has cap member 73 covering said opening 72 thereon. Said cap member 73 covers all of passages 63, 64 and 70 and supports hopper 74 at its upper end portion. A distributing chamber is formed within said cap member 73. Upper portion 75 of shaft 31 projects into said distributing chamber and has rotary distributor 76 which consists of pot portion 77 opposite the opening of hopper 74 for feeding grain and distributing outlet 78 projecting outward and downward diagonally from said pot portion. Said outlet 78 rotates with the rotation of shaft 31 and spreads the grain fed to hopper 74 in distributing chamber 79. By this spreading action of outlet 78, grain is fed to each of passages 63 and 64. In order to prevent the tendency of grain being not fed

to outmost passage 70, arc hopper 80 covering about one third the periphery is provided between upper part 75 of the shaft and the inner wall of cap member 73. As a result, when rotating outlet 78 is passing in said arc hopper 80, grain is fed only into said outmost feeding passage 70.

Shutter valve 82 is pivoted on the inner wall of part 81 connecting cap member 73 and storage hopper 74 in said part. Said valve 82 is opened or closed by means of 10 screw rod 83 inserted through said wall from outside. Screw rod 83 is vertically inserted at shoulder 84 of cap member 73 forming the distributing chamber. Said screw rod 85, when screwed into the chamber, stops the rotation of rotary distributor 76. In order to be stopped independently of the rotation of shaft 31 in this way, said rotary distributor has part 86 of a reduced diameter at the upper end of upper part 75 of shaft 31 slidably and rotatably inserted therein and is pressed against the shoulder of part 75 of said shaft by means of spring 88 between it and nut 87 screwed on part 86. Outlet pipes 89, 90 and 91 are formed and aligned vertically near the respective upper edges of outside walls 43, 52 and 61 of said chambers A, B and C, respectively. Said pipes 89, 90 and 91 communicate with common pipe 92 which has delivery opening 93 at the lower end. Outside walls 43, 52 and 61 of chambers A, B and C, respectively, support suction pipes 94, 95 and 96 opening near inner walls 50, 58 and 69, respectively, of said chambers. Said pipes 94, 95 and 96 are collected into common pipe 97 outside chambers 30 A, B and C, respectively. The outlet of said common pipe 97 is connected with the inlet of cyclone 98. Suction pipe 99 hangs down from above in said cyclone 98 as in any ordinary cyclone. Said pipe 99 is connected with a proper vacuum source (not shown) through pipe 100.

35 A grain mixture fed by hopper 74 to be subjected to the separating treatment is first of all introduced into the distributing chamber by the rotation of rotary distributor 76. A part of the mixture comes into chamber A through passage 70. In chamber A, the mixture is subjected to 40 the separating action on rotating disc 62 as shown in the above with reference to Figure 1. Then, the part of the mixture high in specific gravity or, for example, unhulled rice moves outward in the chamber, rises by being guided on the inner surface of wall 61 and is taken out by delivery pipe 89. Unhulled rice particles low in specific gravity and high in frictional coefficient move to the upper layer inside the cyclone flow of the fluid in the chamber, are sucked into suction pipe 96 opening in this part, arrive at cyclone 98, are therein separated from uncleared rice or others 50 high in specific gravity which had been mixed by mistake and are sent to a collecting place.

Rotary distributor 76, as it rotates, leaves arc hopper 80 and introduces the grain mixture into passages 63 and 64. The grain mixture coming into passage 63 enters 55 chamber C through passage 56 where it is treated just the same as in chamber A. The mixture coming into passage 64 enters chamber B and is subjected to the same treatment as in chamber A. The grain high in specific gravity from each chamber flows out through pipe 93. 60 The grain low in specific gravity and high in frictional coefficient is sucked by suction pipe 97 and is sent to cyclone 98.

As mentioned above, grain can be easily separated according to difference in specific gravity and frictional coefficient from a grain mixture of particles different in specific gravity. The outside wall is stationary in the above explanation but may be made to rotate in the direction reverse to that of the rotation of the disc. While the three-step type apparatus is shown as an exact embodiment, it is needless to say that the apparatus of this invention may be of two or more than three step type without deviating from the spirit of the invention.

I claim:

1. A grain separator comprising a treating chamber 75 consisting of a stationary outside wall and a rotary bot-

tom disc within the periphery of said wall and contiguous therewith, a means of delivering grain to be separated by said separator disposed over said disc at the center of said chamber and a means of removing grain low in specific gravity and high in frictional coefficient disposed near the center in the upper part of said chamber.

2. A grain separator comprising a stationary outside wall expanding outwardly and upwardly, a rotary disc fitted within the peripheral lower end portion of said outside wall to form a separating chamber, a means of feeding a grain mixture to be treated to said chamber, said means opening above the central part of said disc, a means of discharging grain high in specific gravity provided in said outside wall and a means of removing grain low in specific gravity disposed near the center 15 in the upper part of said chamber.

3. A grain separator comprising a base portion, a first outside stationary wall fixed above said base portion, a second outside stationary wall fixed above said first outside wall, a third outside stationary wall fixed above the 20 second outside wall, a shaft having its lower end supported by said base portion extending axially through said outside walls, a first rotary disc on said shaft within the lower periphery of said first outside wall forming with said first outside wall a third chamber, the second rotary disc on said shaft within the periphery of said second outside wall and having a passage therein to feed untreated grain to the third chamber and forming with said second 25

outside wall a second chamber, a third rotary disc on said shaft within the periphery of said third outside wall and having two passages therein to feed untreated grain to said second and third chambers and forming with said third outside wall a first chamber, a rotary distributor mounted on said shaft above said first chamber to feed untreated grain to said first chamber and to said two passages, a storage hopper disposed above said distributor, and means in each chamber to remove separated grain from each chamber.

4. A grain separator as claimed in claim 3 in which the means in each chamber to remove separated grain comprise an outlet pipe for removing separated grain high in specific gravity, said outlet pipe being provided in the upper part of the outside stationary wall of each chamber, and a suction pipe for each chamber being supported by each of said walls and opening near the inside of and in the upper part of each chamber.
